CHAIR

Filed Dec. 3, 1934

UNITED STATES PATENT OFFICE

2,049,659

CHAIR

Percy F. Parrott, Toledo, Ohio

Application December 3, 1934, Serial No. 755,697

4 Claims. (Cl. 155—139)

This invention relates to furniture.

This invention has utility when incorporated in foldable chairs made of sheet material.

Referring to the drawing:

Fig. 1 is a plan of a blank of sheet material which is foldable into a chair of the invention herein;

Fig. 2 is a bottom plan of the chair in partially collapsed position;

Fig. 3 is a side elevation of the chair of the invention herein;

Fig. 4 is a plan view of the chair of Fig. 3;

Fig. 5 is a bottom plan view of the chair of Fig. 4;

Fig. 6 is a section on the line VI—VI, Fig. 4; and

Fig. 7 is a section on the line VII—VII, Fig. 3, showing a modified form of reinforcement insert.

The invention herein comprises a chair which can be made from sheet stock such as cardboard, corrugated board or like materials, and when folded, as shown in the disclosure herein, will serve as a suitable support or chair for even a full grown and heavy person. The chair may be collapsed into a flat position, thereby allowing such to be easily transported and stored.

The chair may be made from blank 1 which comprises rectangular or chair back forming portion 2 and additional chair side forming portions 3, 4, 5, and 6. These side providing means are partially defined by score lines 7, 8, 9, and 10.

In the completed chair, edge 11 of the blank 1 may contact edge 12 and be held together therewith by fabric tape 13, (Fig. 3), which fabric tape may also be placed over any of the score lines which are subject to folding and unfolding, thereby increasing the life of the chair. This fabric tape may be of linen or other durable material and of such strength and size as to give long life to the chair.

The portion 2 is provided with first extension 14 therefrom partially defined by score lines 15, 16, which extension terminates in end portion 17 of somewhat fan shape provided with intermediate slot 18. The portions 3, 6, are provided with diagonally extending score lines 19 partially defining triangular extensions 20. The portions 4, 5, are provided with a second extension 21 having the score line 9 continued thereacross, said extension being defined by score line 22 as to the portions 4, 5, while diagonal score lines 23 extend from the outer corners of the extension 21 to intersect at the score lines 9 and 22. In the assembly of the blank into an article of furniture such as a chair as hereinbefore disclosed, the edges 11,

12, are brought together and assembled by tape or any suitable stitching means. The blank is folded on the lines 7, 8, 9, and 10, so that there is formed a tube having a pentagonal cross section in which the portions 2, 3, 4, 5 and 6 provide supporting sides. 5

This structure, being a five sided form, would ordinarily not be readily foldable into collapsed position or flat form. To this end score line 24 extending intermediately of the portion 1 divides 10 such so that the tube may be collapsed to a flat position as shown in Fig. 2. The extension 14, 17, is folded on the line 15 so that an undue length is not obtained in the folded position.

In setting up the blank the tubular support is 15 opened and the portion or extension 14 folded on itself downwardly against the inner side of and to reinforce the back formed by portion 2. The extension is further folded on the line 16 so that the portion 17 extends outwardly and horizontally 20 from said means toward other side means there to abut and form a seat portion. Within the tube may be placed reinforcing member 25 fastened to one side of the tube by stitching 26 and providing upstanding sheets on the upper edges of 25 which this partial seat portion 17 may rest. The seat is completed by extension 21 also downwardly foldable in on itself and into horizontal position over the portion 17 toward other side means. In folding the portion 21 from the two side 30 means 4, 5, which are angularly extending from each other, the score lines 23 allow the seat excess or intermediate portion of this extension 21 to fold into a downwardly extending rib 27 which extends through the slot 18 of the portion 17, 25 thereby providing an additional reinforcement for the seat. Following the assembly of the seat portion the sides 20 may be turned inwardly along score lines 19, thereby forming reinforced sides and also folding against the back extension 14, 40 locking or holding the chair into assembled position. Reinforcements 25 may extend between non-adjacent corners of the polygonal cross section of the chair support with the rib 27 extending downwardly through the slot 18 and between 45 the reinforcements 25.

A modified form of reinforcement is shown in Fig. 7, in which strips 28 of sheet material may have their ends attached to opposing sides of the chair by stitching 26 and angularly extend toward and from the approximate center of the tube. Strips 29 may be used as additional reinforcing means held in between the angular extent of the reinforcement strips 28 and opposing intersecting sides of the chairs. 50 55

It will be seen that the chair can be readily collapsed or readily set up and while the blank is shown as a single piece in Fig. 1, the various portions may be cut separately for economy in cutting and assembled by fabric tape or stitching. However, the resulting blank after assembly is simple and constitutes one piece for storage and will support a great weight.

The pentagonal or oblique angular shape of 10 the chair as produced from sheet material, in providing an angle at the chair front or opposite the back, allows the user to readily arise and seat himself by permitting the feet to be brought back under the knees. In that the straight front, 15 solid or sheet sides of furniture of this type prevents the feet from being placed under the knees, this pentagonal construction allows freedom of body movement in chair use.

What is claimed and it is desired to secure by 20 Letters Patent is:

1. In an article of furniture, stiff sheet material formed into side means hinged together and angularly disposed to complete a tubular oblique angular polygonal supporting section, an extension hingedly connected to one of said side means 25 and foldable downwardly, the end portion of the extension foldable toward other side means of said tubular section, and having certain of its edges binding against other side means to horizontally position said end portion of the extension to provide a seat portion.
2. In an article of furniture, stiff sheet material formed into side means hinged together and angularly disposed to complete a tubular oblique angular polygonal supporting section having corners between said side means, two of said side means having an extension such that when folded to extend horizontally, said extension is formed

with two triangular portions with inner abutting sides and a depending rib, whereby said extension provides a seat portion.

3. In an article of furniture, stiff sheet material formed into side means hinged together and angularly disposed to complete a tubular oblique angular polygonal supporting section, an extension hingedly connected to one of said side means and intermediately foldable downwardly on itself to provide a double thickness back portion, the end portion of the extension being bent with certain of its edges extending horizontally and binding against other side means to form a seat portion hingedly connected to said back and extending away from the back.

4. In an article of furniture, stiff sheet material formed into side means hinged together and angularly disposed to complete a tubular oblique angular polygonal supporting section, a first extension hingedly connected to one of said side means and intermediately foldable downwardly on itself to provide a double thickness back portion, the end portion of the first extension being bent with certain of its edges extending horizontally to form a seat portion hingedly connected to said back and having a slot extending away from the back, and a second extension hingedly connected to another of said side means and foldable downwardly toward the first extension, the end portion of the second extension foldable horizontally toward the back and against said seat portion as a supplemental section formed with two triangular portions with inner abutting sides, and a depending rib projecting through said slot whereby said horizontal extensions provide seat portions.

PERCY F. PARROTT.
